CLAIM

The ornamental design for a set of orthopedic bone block assemblies, as shown and described.

DESCRIPTION

FIG. 1 is a perspective view of a set of orthopedic bone block assemblies showing our new design;

FIG. 2 is a front elevation thereof shown on a reduced scale; FIG. 3 is a rear elevation thereof;

FIG. 4 is a left side elevation thereof, the side opposite being a mirror image;

FIG. 5 is a top plan thereof;

FIG. 6 is a bottom plan view thereof;

FIG. 7 is a bottom plan view thereof with the environmental structures shown in an alternate position, the side opposite of the assembly shown on the left side of the drawing being a mirror image; and,

FIG. 8 is a left side elevation thereof showing the environmental structures in an alternate position.

The broken lines in the drawings located on the two bone blocks are included for the purpose of defining the boundaries of the claimed subject matter and form no part of the claimed design. The other broken lines are included for the purpose of illustrating environmental subject matter and form no part of the claimed design.
